(57) CLAIM

We claim the ornamental design for a container for liquids, as shown and described.

DESCRIPTION

FIG. 1 is a perspective view showing our new container for liquids;

FIG. 2 is a front elevational view thereof;

FIG. 3 is top plan view thereof;

FIG. 4 is a side elevational view taken from the right of FIG. 2;

FIG. 5 is a bottom plan view thereof; and,

FIG. 6 is a side elevational view taken from the left of FIG. 2.
